UNITED STATES PATENT OFFICE.

ARTURO DE LUNA, OF BUFFALO, NEW YORK.

SANITARY BEDPAN.

Application filed October 21, 1926. Serial No. 143,055.

This invention relates generally to sanitary covers, the invention having more particular reference to a novel type of sanitary cover used to cover a bed pan such as used during 5 an illness confining a person to bed.

The invention has for an object the provision of an improved sanitary cover, for the purpose described, of simple and inexpensive construction.

10 A further object of the invention is the provision of an improved sanitary cover embodying certain novel features which will render the said device more useful and efficient.

15 For further comprehension of the invention, and of the objects and advantages thereof, reference will be had to the following description and accompanying drawings, and to the appended claims in which the 20 various novel features of the invention are more particularly set forth.

Fig. 1 of the drawings is a top plan view illustrating my improved sanitary cover applied to a bed pan.

25 Fig. 2 is a transverse sectional view taken on the line 2—2 of Fig. 1.

Fig. 3 is an enlarged fragmentary view thereof, as viewed from the line 3—3 of Fig. 2.

30 The bed pan 10, is of common ordinary construction and design, such as generally used during an illness confining a person to bed, and is provided with a handle 11, a spout 12, and an aperture 13.

35 As here embodied my improved sanitary cover comprises a main element 14, adapted to encircle the above mentioned aperture 13, and to cover the portion of the bed pan 10 adjacent to the aperture 13, and is provided 40 with flaps 15, extending therefrom, formed therein by slotting the main element 14, as at 16, so as to permit the said flaps 15 to cover the edge of the aperture 13 of the bed pan 10, so as to provide a sanitary cover for 45 the said bed pan.

The attaching means provided to attach my improved device to the bed pan 10, comprises a rod 17, hinged as at 18, at its extremities, to raised elements 19 of the bed 50 pan 10, located under the above mentioned spout 12. The pin 20 is attached, at its extremities to the supports 21, also attached to the rod 17, and depending therefrom. The flat spring 22, is attached as at 23, by 55 rivets or the like to the spout 12, and is positioned so as to allow a finger 24 integral

with one side of its free extremity to normally hold the pin 20 in contact with the spout 12 of the bed pan 10. Projecting fasteners 27 are attached to the bed pan 10, 60 adjacent to the handle 11, and are adapted to engage elongated slots 28, formed in the main element 14, the fasteners being insertable through the enlarged portions 29 of the said elongated slots 28.

65 The main element 14 of my improved sanitary cover is provided with extended portions 25, adapted to engage over the spout 12 of the bed pan 10, and terminating in an extremity, or tongue 26, which is positioned between the rod 17 and the pin 20, between the pin 20 and the spout 12. The latter described construction being such as will permit the attaching means as described above to securely hold my improved sanitary cover in place on the bed pan 10.

70 It will be understood that my improved sanitary cover may be made of heavy paper, fibre paper, or the like, or of any similar cheap material which may be discarded and 75 replaced, being used but once.

75 While I have above described the preferred form, construction and arrangement of the several elements employed, it will be understood that the device is, nevertheless, 80 susceptible of considerable modification therein, and I therefore reserve the privilege of resorting to all such changes as may be fairly embodied within the spirit and scope 85 of the invention as claimed.

90 Having thus described my invention, what I claim as new and desire to protect by Letters Patent of the United States is as follows:

95 1. A sanitary cover for bed pans comprising a main element adapted to encircle the aperture of the said bed pan, and to cover the portion adjacent to the said aperture, and provided with flaps extending therefrom, so as to permit the said flaps to 100 cover the edge of the said aperture in the said bed pan, said main element provided with extended portions, adapted to engage the spout of the said bed pan, and terminating in a tongue, elongated slots provided with enlarged portions formed in the said main element, adapted to be engaged by projecting fasteners attached to the said bed pan, as a means of attaching the said sanitary cover to the said bed pan.

105 2. A sanitary cover for bed pans, comprising a main element adapted to encircle

the aperture of the bed pan, and to cover the portion adjacent the aperture, and provided with flaps extending therefrom, so as to permit the said flaps to cover the edge of the said aperture in the bed pan; the said main element being provided with extended portions, adapted to engage the spout of the bed pan, and terminating in a tongue

adapted to be clamped by clamping means to the bed pan, and the main element being ¹⁰ also formed with elongated slots with enlarged portions, adapted to be engaged by projecting fasteners from the bed pan.

In testimony whereof I have affixed my signature.

ARTURO DE LUNA.
